UNITED STATES PATENT OFFICE.

JACOB M. LONDON, OF BROOKVILLE, PENNSYLVANIA, ASSIGNOR TO SULLIVAN MACHINERY COMPANY, OF CLAREMONT, NEW HAMPSHIRE, A CORPORATION OF MASSACHUSETTS.

MINING MACHINE.

Application filed October 30, 1915, Serial No. 58,899. Renewed September 22, 1924.

This invention pertains to improvements in mining machinery and more particularly, though not exclusively, to improvements in chain mining machines of the entry cutting type wherein the actuating and cutting appliances of the mining machine are pivotally mounted.

In machines of this class, the cutting element has heretofore been mounted on a pivot 10 on a truck, the machine and the truck being advanced towards the work with the cutter bar held at an angle relative to the axis of the entry to be cut, then when the cutter bar has cut its way into the coal, the cutter bar 15 is swung laterally across the axis of the entry and then preferably withdrawn to complete the undercutting of a kerf.

The general system before described and, so far as I know, first disclosed in Letters 20 Patent No. 1,077,418 to Edward McGowan is excellent. Five disadvantages, however, may be noted. The first of these is the height of the kerf which is necessarily a considerable distance above the mine bottom, there- 25 by making a center-cut rather than an undercut. This is peculiarly disadvantageous in "low coal".

The second, also peculiarly disadvantageous in "low coal" is the height of the apparatus, which necessarily includes not only 30 the height of the mining machine but all, or a considerable portion of the height of the truck.

The third disadvantage is the necessity 35 of providing turn outs into each entry and tracks up to the face of the coal at the end of the entry.

The fourth disadvantage is the liability of 40 the tracks to sag or be uneven, which as the cutter bar is advanced into the work, binds the cutter bar. It is clear that even a slight deviation of the tracks from a single plane, will result in either a raising or a lowering 45 of the truck, which in turn, will cause the cutter bar to bind on the top and on the bottom of the kerf.

The fifth, is the instability of the truck which must, in most instances, be of comparatively narrow gage and short wheelbase.

50 In the accompanying drawings I have shown for purposes of illustration one embodiment which my invention may assume in practice, in which drawings

Fig. 1 is a plan of a sliding swivel pan;

Fig. 2 is a side elevation thereof;

Fig. 3 is a vertical sectional elevation on the line 3—3 of Fig. 1;

Fig. 4 is a vertical sectional elevation on the line 4—4 of Fig. 1;

Fig. 5 is a side elevation of a mining machine, and a sliding swivel pan mounted on a swivel truck, and

Figs. 6 and 7, illustrate various operations of the machine.

Referring to the drawings, I have shown 65 a guiding and supporting element typified by the pan 8 on which is preferably mounted, for sliding, guided movement, longitudinally sliding supporting means typified by the turntable base 9, which is preferably round, 70 as illustrated.

To keep the cutter bar as low as possible, I prefer to dispense with any superimposed turntable member and to provide a rotatable turntable portion 10 provided with attachment means such as the cap screws 11, adapted to engage the bottom of the mining machine, which may be of the usual sliding bed type. To increase the surface of the mining machine in rotative-sliding contact with the turntable base 9, I preferably attach one, or more projecting members to the sides of the mining machine, typified by the angle irons 12. These may conveniently be used to lock the mining machine in any desired angular relation to the axis of the pan 8. To this end I may provide locking means which may comprise pins 13 adapted to pass through holes in the flanges of the angle irons 12 and enter any one of a plurality of 85 holes 14 in the turntable base 9.

The pan 8 preferably comprises side members 15 preferably of angle iron and preferably held in parallel relation by bottom plates 16 on which the whole apparatus may 95 be slid along the mine bottom to properly position the mining machine for its entry cutting work. During the cutting operation, however, the pan is preferably stationary while the mining machine is fed to the work 100 by being fed forward with the turntable base 9 which is mounted for sliding guided movement on the pan 8, and otherwise operated as hereinafter described.

I may provide rabbeting 17 preferably attached to the turntable base 9 and engaging

longitudinally extending plates 18. These plates 18 are preferably located so that the turntable base 9 may rest upon them, thus providing an ample bearing surface. To this end I preferably position them flush with the top of the flanges of the angle irons 15 by providing spacing members 19 and 20.

To construct the pan without undue weight and to provide convenient access to the cap screws 11, I preferably space the bottom plates 16 a considerable distance apart. It will be noted that the construction of the pan illustrated keeps the mining machine as near the floor of the mine as is consistent with the provision of longitudinal guiding means and pivotal supporting means.

If desired, the mining machine may be detached and be used for sliding operation on the mine bottom for regular long wall or room and pillar work.

My invention is peculiarly advantageous for use in low coal. In driving entries in low coal it is desirable to dispense with "brushing" or increasing the height of the entry until the entry has been advanced or driven a considerable distance. I provide a truck 40 for transporting the pan and mining machine about the main entries. As the cross entries are transverse to the main entries, I provide a swivel mounting 41 on the truck to enable the pan and mining machine to be swung across the axis of the main entry and discharge in alignment with the cross entry to be operated upon.

To hold the mining machine in fixed relation to the pan during transportation on the truck and during its sliding traverse, I preferably provide stops 21 against which the mining machine may abut when in its extreme rearward position in the frame, and cooperating with side members 23, which may be integral with the angle irons 15, to prevent swinging movement when the mining machine is in the rearward position. To prevent or permit forward movement of the mining machine on the pan as desired, I provide a stop 22 which is adapted to be engaged by a latch 101 on the mining machine.

To insure the proper positioning of the apparatus on the truck, I provide supplementary positioning means comprising a latch 24 adapted to engage a stop on the swinging truck frame. To prevent swinging of the swinging truck frame 43, I provide locking means 102 for preventing rotation of the turntable. In a truck which is propelled by the actuator of a separable mining machine as is common in the art, the above complex locking system is essential to prevent not only longitudinal but swinging relative displacement of the truck and driving mechanism owing to the provision of turntable means.

As the details of the truck driving mechanism form no part of the present invention, no description thereof is herein made.

The mining machine 7 may be of any preferred type but preferably is provided with a cutter bar adapted to be held rigidly in fixed relation to the machine, an actuator and flexible feeding tension means which preferably includes a feed chain 25 engaging winding means as a winch 26.

The winch 26 is rotated by the actuator of the mining machine. By anchoring the flexible tension means to a fixed support and engaging the former with the winding means, the actuator of the mining machine will pull itself and the sliding swivel pan to the work, as shown in Fig. 6. When the pan is adjacent the face of coal at the end of the entry and aligned therewith, the latch holding the mining machine back in the pan, may be lifted and the machine will then slide forward on the pan. When clear of the lateral positioning members 23, the machine may be swung on the turntable to the angle shown in Fig. 7, locked there by the pins 13, and then advanced into the work until the position shown in Fig. 7 is attained. The pins may then be removed and the chain adjusted, as shown in Fig. 7, to swing the cutter bar across the axis of the entry thereby cutting a kerf. If desired, the machine may then be retracted while sliding on the pan, to complete a kerf, as indicated by dotted lines in Fig. 7.

In the operation of my improved construction in entry cutting, the machine is usually run into the entry on the mine track, and the pan with the mining machine supported thereon is then unloaded from the truck until supported by the mine bottom, the same being preferably disposed substantially in alignment with the track. Thus, it will be observed that the bar is enabled to operate very close to the bottom and in a plane substantially beneath the plane of the track rails, in such a manner as materially to increase the tonnage, about a ton of additional coal being mined at each cut, and at the same time to minimize the expense and difficulties incident to the removal of the stratum of coal lying between the bottom of the kerf and the mine bottom. Obviously, through the use of my improved construction, the pan may also be readily used in driving entries where, for one reason or another, it is undesirable or impossible to provide a track, the pan and machine then being bodily slid along upon the mine bottom into the desired location. As a result of my improved construction, it will also be observed that the pan resting upon the bottom of the mine affords a very stable support and, owing to its rigidity and unitary structure, insures the maintenance of the cutter bar in a given plane, thus preventing

any cramping of the cutter bar. Attention is also directed to the fact that by the use of my improved apparatus which is capable of operating very close to the bottom, the same is well adapted to use in low seams of coal. It will also be noted that through the use of my improved construction, not only may the mining machine be transported from place to place on the truck and, if desired, used as an ordinary truck-mounted entry driving machine when thereon, or used separately with the pan in other relations, but that the mining machine may itself be readily removed from the pan and used in any desired relation without in any way interfering with its usefulness as a standard type of machine.

If it is desirable to make a cut at an inclination to the mine bottom the pan may be only partially unloaded from the truck, the front end of the pan being supported by the mine bottom and the rear end by the truck, and the mining machine may be moved down the sloping pan and may be operated when thereon to make the sumping, transverse, and withdrawal cuts in the same manner in which these cuts are made when the pan rests entirely on the mine bottom. Since the weight of the mining machine and pan will tilt the truck when the pan and machine are being unloaded therefrom, the rear end of the pan may be supported at substantially the height of the truck from the mine bottom or on the forward end of the truck closely adjacent the mine bottom, by merely adjusting the position of the rear end of the pan on the truck, and it is possible because of this adjustment to so place the pan that the cutter bar will cut a non-horizontal kerf the front edge of which will contact with the mine bottom proper in advance of the face of the entry. It is highly desirable in making entry cuts to cut on the mine bottom or as closely adjacent thereto as possible. With the pan resting directly on the mine bottom, the kerf that is cut is substantially on the mine bottom, the distance between the mine bottom and the cutter bar being limited only by the depth of the pan which, as is clearly shown in the drawings, has been made a minimum. By using the cutting mechanism in inclined position, i. e. when on the sloping pan as described above, a part of even the strata next the mine bottom may be removed, leaving only shallow, wedge-shaped blocks of coal, the base of the wedge being adjacent the entry face and the point thereof coming at the place where the end of the cutter bar touches the mine bottom. It is thus seen that by my improved construction the mining machine and pan may be moved about the mine on the truck and may be unloaded from the truck at any angle thereto; the mining machine and pan

may be partially unloaded from the truck for cutting on the pan at an angle to the horizontal; or the mining machine and pan may be completely unloaded from the truck for cutting a kerf in the face of an entry substantially on the mine bottom, in which case the pan functions as a skid for moving the mining machine from the truck to the entry face and as a guiding means during the cutting operation. These and other advantages of my improved construction will, however, be clearly apparent to those skilled in the art.

It will be understood that my invention is not limited to that embodiment of my invention illustrated and described but may be greatly varied within the scope of the appended claims.

What I claim and desire by Letters Patent to procure, comprises:—

1. Mining apparatus comprising in combination a relatively long, low, solid, normally stationary, guiding means adapted to rest directly upon a mine bottom, a flat, relatively thin turntable base, resting directly on said guiding means, adapted to move in guided relation thereto, and to directly receive on its flat top a complete, independently operative, mining machine as a unit, for rotary movement thereon, whereby the cutter bar of the mining machine is brought substantially to the surface of the bottom of the mine.

2. Mining apparatus comprising in combination a relatively long, low, solid, normally stationary, guiding means adapted to rest directly upon a mine bottom, a flat, relatively thin turntable base, resting directly on said guiding means, adapted to move in guided relation thereto, and to directly receive on its flat top a complete, independently operative, mining machine as a unit, for rotary movement thereon, whereby the cutter bar of the mining machine is brought substantially to the surface of the bottom of the mine, and means carried by the mining machine and cooperating with said base, for locking the machine in the desired rotary position on the base.

3. Mining apparatus comprising, in combination, a truck, a guiding frame reciprocal relative to said truck and slidably over the mine bottom, a turn-table element slidably mounted on said guiding frame, a mining machine mounted on said turn-table element and having a cutter bar disposed in adjacent parallelism to said guiding frame, means for holding said mining machine in fixed relation to said frame, and means for holding said frame in fixed relation to said truck.

4. Mining apparatus comprising, in combination, an elongated relatively low frame slidable on the mine bottom, a mining machine operatively supported by said frame

- and having a cutter bar projecting therefrom in adjacency to the top of said frame, said cutter bar being substantially in a plane parallel to said frame, a sliding support for said mining machine operatively interposed between said frame and said mining machine, a pivot connecting said sliding support and said mining machine, and flexible feeding means for advancing said sliding support lengthwise of said frame and for swinging said mining machine on said pivot to cut an arcuate kerf across the end of said frame substantially the depth of said frame above the mine bottom.
- 15 5. A mining machine comprising, in combination, a truck, a removable pan slideable over the mine bottom and slidably mounted on said truck, a turntable element carried by said pan, a mining machine slidably mounted on said turntable element and having a cutting element normally disposed in a plane closely adjacent the plane of said pan, and means connected to said mining machine for sliding said machine relative to said pan and for sliding said pan relative to said truck.
- 30 6. Mining apparatus comprising, in combination, a mining machine, a pivotal support therefor, a frame adapted to rest on and in adjacency to the mine bottom on which said pivotal support is traversed adjacent the mine bottom in guided supported relation during the operation of said mining machine, a wheeled truck on which said frame with said mining machine mounted thereon may be mounted, and locking means for holding said mining machine relative to said frame and said truck during movement of said truck.
- 35 40 7. Mining apparatus comprising, in combination, a mining machine, a pivotal support therefor, a frame adapted to rest on and in adjacency to the mine bottom on which said pivotal support is traversed adjacent the mine bottom in guided supported relation during the operation of said mining machine, a wheeled truck on which said frame with said mining machine mounted thereon may be mounted, and locking means for holding said mining machine relative to said frame and said truck during mining machine actuated movement of said truck.
- 45 50 8. Mining apparatus comprising, in combination, cutting appliances, a pivotal support therefor, a frame adapted to rest on and in adjacency to the mine bottom on which said pivotal support is traversed adjacent the mine bottom in guided supported relation during the operation of said cutting appliances, a wheeled truck on which said frame with said cutting appliances mounted thereon may be mounted, and means for holding said cutting appliances relative to said frame and said truck during movement of said truck.

9. Mining apparatus comprising, in combination, a mining machine, a pivotal support therefor, a frame adapted to rest on and in adjacency to the mine bottom on which said pivotal support is traversed adjacent the mine bottom in guided supported relation during the operation of said mining machine, a wheeled truck on which said frame with said mining machine mounted thereon may be mounted, and means for holding said mining machine relative to said frame and said truck during movement of said truck.

10. Mining apparatus comprising, in combination, a mining machine, a pivotal support therefor, a frame adapted to rest on and in adjacency to the mine bottom on which said pivotal support is traversed adjacent the mine bottom in guided supported relation during the operation of said mining machine, a wheeled truck on which said frame with said mining machine mounted thereon may be mounted, and means for holding said mining machine relative to said frame and said truck during mining machine actuated movement of said truck.

11. Mining apparatus comprising, in combination, a rigid guiding frame adapted to lie upon a mine bottom during cutting and mining mechanism slideable thereon during cutting and providing a cutter bar narrower than said frame but disposable during cutting at angles to said frame at either side of the latter whereby a kerf wider than said frame may be cut, and a truck upon which said guiding frame is supportable in whole or in part for transport or inclined cutting respectively.

12. Mining apparatus comprising, in combination, a rigid guiding frame adapted to lie upon a mine bottom during cutting and mining mechanism slideable thereon during cutting and including a mining machine having a rigidly projecting cutter bar and disposable in different angular relations to said frame so that said bar may project at either side of said frame during movement therealong whereby said bar may cut at either side of said frame, and a truck upon which said guiding frame is supportable in whole or in part for transport or inclined cutting respectively.

13. Mining apparatus comprising, in combination, a rigid guiding frame adapted to lie upon a mine bottom during cutting and mining mechanism slideable thereon during cutting and providing a cutter bar narrower than said frame but disposable during cutting at angles to said frame at either side of the latter whereby a kerf wider than said frame may be cut, and a truck upon which said guiding frame is supportable in whole or in part for transport or inclined cutting respectively, said mining mechanism effecting cutting of kerfs whose lower bounding

surface is closely adjacent the upper surface of said guiding frame.

14. Mining apparatus comprising, in combination, a rigid guiding frame adapted to lie upon a mine bottom during cutting and mining mechanism slideable thereon during cutting and including a mining machine having a rigidly projecting cutter bar and disposable in different angular relations to said frame for movement therealong whereby said bar may cut at either side of said frame, and a truck upon which said guiding frame is supportable in whole or in part for transport or inclined cutting respectively, said mining mechanism effecting cutting of kerfs whose lower bounding surface is closely adjacent the upper surface of said guiding frame.

15. Mining apparatus comprising, in combination, a rigid guiding frame adapted to lie upon a mine bottom during cutting and mining mechanism slideable thereon during cutting and providing a cutter bar narrower than said frame but disposable during cutting at angles to said frame at either side of the latter whereby a kerf wider than said frame may be cut, and a truck upon which said guiding frame may be suitably disposed in parallelism to the path of movement of said truck for transport about a mine.

16. Mining apparatus comprising, in combination, a guiding frame adapted to lie upon a mine bottom during cutting and mining mechanism slideable thereon during cutting and including a mining machine having a rigidly projecting cutter bar and disposable in different angular relations to said frame for movement therealong where-

by said bar may cut at either side of said frame, and a truck upon which said guiding frame may be suitably disposed in parallelism to the path of movement of said truck for transport about a mine.

17. Mining apparatus comprising, in combination, a guiding frame adapted to lie upon a mine bottom during cutting and mining mechanism slideable thereon during cutting and providing a cutter bar narrower than said frame but disposable during cutting at angles to said frame whereby a kerf wider than said frame may be cut, and a truck upon which said guiding frame may be suitably disposed in parallelism to the path of movement of said truck for transport about a mine, said mining mechanism effecting cutting of kerfs whose lower bounding surface is closely adjacent the upper surface of said guiding frame.

18. Mining apparatus comprising, in combination, a guiding frame adapted to lie upon a mine bottom during cutting and mining mechanism slideable thereon during cutting and including a mining machine having a rigidly projecting cutter bar and disposable in different angular relations to said frame for movement therealong whereby said bar may cut at either side of said frame, and a truck upon which said guiding frame may be suitably disposed in parallelism to the path of movement of said truck for transport about a mine, said mining mechanism effecting cutting of kerfs whose lower bounding surface is closely adjacent the upper surface of said guiding frame.

In testimony whereof, I have signed my name to this specification.

JACOB M. LONDON.
